CONVERSION OF PROPYLENE AND ISOBUTYLENE TO ALLENE AND METHYLACETYLENE

Milton Jones Hogsed, Wilmington, Del., assignor to E. I. du Pont de Nemours and Company, Wilmington, Del., a corporation of Delaware

Application March 20, 1957, Serial No. 647,358

3 Claims. (Cl. 260—678)

This invention relates to an improved method for preparing allene, and more particularly to an improved method for converting isobutylene and propylene to allene and methylacetylene.

Allene, the simplest diene hydrocarbon, offers special opportunities for the synthesis of a wide variety of chemicals because of its highly reactive nature. There are a number of published methods for its preparation, some of which are primarily of academic interest. One method which was recently described (U.S. Patent 2,763,703, issued to J. Happel and C. J. Marsel on September 18, 1956) is the demethanation of isobutylene at 800–900° C. in the presence of 80–90 mole percent of steam. This procedure produces one mole of methane for every mole of allene or methylacetylene. The methane is a waste by-product. Dehydrogenation of propylene produces only hydrogen as a by-product, but all such dehydrogenation methods hitherto described are economically unattractive because they produce the desired allene at very low yield. A novel allene synthesis which yields allene efficiently and economically would therefore be highly desirable. It is the object of the present invention to provide such a process.

According to this invention, allene is produced by contacting propylene or isobutylene at a pressure below 100 mm. mercury with a metal filament heated to at least 900° C. at a contact time of less than 0.01 second.

The attached drawing (Fig. I) illustrates in simple

2

tions of the equipment illustrated may be employed without departing from the scope of the present invention. In operation, the olefin, isobutylene or propylene, is passed over a heated filament at a contact time of less than 0.01 second and under a pressure below 100 mm. At start-up the system is flushed with nitrogen while the filament is heated to the desired temperature. After the desired temperature has been attained, nitrogen flow is discontinued and the flow of olefin is started. After predetermined volume of the olefin has been put through the reactor, the system is flushed with nitrogen. Products are collected in a trap cooled to –196° C. with liquid nitrogen. The product in the trap is then transferred to a receiver by bleeding into an evacuated container and stored.

The time of reaction is calculated by determining contact time, which is defined as the volume of the reaction zone divided by the throughput volume at reaction temperature. The throughput at reaction temperature is calculated by multiplying the volume of gas at standard conditions by $[1 + T^\circ \text{ K.} \times 0.00366^1]$. Space velocity, V_s , is the hourly throughput volume at standard conditions divided by the reaction zone volume.

$$25 \text{ Contact time, seconds} = \frac{3600 \text{ seconds}}{T^\circ \text{ K.} (0.00366) V_s} \frac{9.83 \times 10^5}{T^\circ \text{ K.} \times V_s}$$

The examples which follow illustrate but do not limit this invention.

30 Example I

Referring to the drawing (Fig. I), isobutylene was passed through the wet test meter, then through the needle valve that controlled the flow rate. After leaving the pyrolysis chamber, the pyrolyzate was condensed in a liquid nitrogen-cooled trap. The significant improvements in yields achieved by low pressure pyrolysis over a hot platinum wire at contact times of less than 0.01 second are shown in the table below, where the values obtained by the use of a heated metal filament are compared with pyrolysis yields disclosed in the literature obtained by conventional heating methods.

Run	Temp., ° C.	Contact Time per sec.	Isobutylene Consump- tion, Percent	Combined A+MA ^b Yield	A/MA ^b
Quartz Furnace	900	0.04	13.4	28.4	-----
Isobutylene alone over Pt wire at 32–35 mm.	1,015	• 0.001 to 0.01	54.0	52.0	1/0.9
Chrome-steel Furnace	850	0.14	11.8	36.0	-----

to current. The pyrolysis conditions and results are summarized in the table which follows:

Metal Packing	Contact Time per sec.	Maximum Temp., °C.	Propylene Consumption, percent	Combined Yield of Allene And MeAc, percent	Liquid N ₂ -Cooled Condensate Composition Analysis		
					Allene, percent	MeAc, percent	Ethylene, percent
Nichrome.....	0.002	950 to above M.P. of Nichrome.	17	28	1.6	1.4	5
Do.....	0.001	1,010	36	23	3.7	3.8	12
Pt Gauze.....	0.0002	1,040	7	25	1.0	0.6	2
Do.....	0.0005	1,400	16	25	2.3	1.3	4
Do.....	0.0002		40	17	31	3.2	10

Example III

Propylene was pyrolyzed at 50 mm. in the manner described above, using coiled platinum wire heated to over 1000° C. by resistance to current from a transformer. The contact time was estimated as being less than 0.01 sec. Allene and methylacetylene were produced in a combined yield of 26% at a propylene consumption of 23%. Yields were negligible at pressures above 100 mm. under similar temperature conditions and contact times.

The highly improved yields obtained by the process of the present invention primarily result from the use of contact times below 0.01 second, as shown by the examples.

Although in the examples platinum and Nichrome have been used, it is to be understood that this is only for convenience and that there is nothing critical about these materials. In their place, there can be used other metals or alloys of high resistivity in the form of gauze or filament.

The pyrolysis is effected at temperatures in the range of 900-1600° C. at contact times of 0.001 to 0.01 sec. Very short contact times are essential to obtain the best balance of olefin consumption with product yield.

The isobutylene and propylene employed can be of reagent or commercial quality and can be of petroleum origin or otherwise prepared. Isobutylene and propylene not converted by one pass through the reaction system may be continuously recycled.

The process of this invention is operated under reduced pressures, i.e., pressure of less than 0.13 atmosphere and preferably below 0.08 atmosphere. This has the practical advantage of markedly increasing the throughput capacity of the equipment and thus makes it possible to utilize it at maximum efficiency. By avoiding the use of steam, costs are reduced and the recovery of the desired allene is simplified.

The process of this invention is an advantage over prior methods by making it possible to convert isobutylene

and propylene in good yields and good conversion to the highly reactive allene, and its isomerization product, methylacetylene.

I claim:

1. A process for the preparation of allene and methylacetylene which comprises passing an olefin of the class consisting of isobutylene and propylene at a pressure below 100 mm. mercury over a metallic filament of high resistivity heated to at least 900° C. at a contact time of less than 0.01 second, cooling the resulting products, and separating allene and methylacetylene from said reaction products.

2. A process for the preparation of allene and methylacetylene which comprises passing propylene at a pressure below 0.08 atmosphere over a metallic filament of high resistivity heated to a temperature of 900° C. to 1600° C. at a contact time of 0.0002 to 0.01 second, cooling the resulting products, and separating allene and methylacetylene from said reaction products.

3. A process for the preparation of allene and methylacetylene which comprises passing isobutylene at a pressure below 0.08 atmosphere over a metallic filament of high resistivity heated to a temperature of 900° C. to 1600° C. at a contact time of 0.0002 to 0.01 second, cooling the resulting products and separating allene and methylacetylene from said reaction products in a ratio of allene to methylacetylene of greater than one.
